Primary Examiner — Jae Liang*Assistant Examiner* — Samantha Lynne Brodowski(74) *Attorney, Agent, or Firm* — Merchant & Gould P.C.(57) **CLAIM**

The ornamental design for a bag as shown and described.

DESCRIPTION

FIG. 1 is a perspective view of a bag;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view.

The dashed-dashed broken lines represent portions that form no part of the claimed design.

The dashed-dot broken lines represent boundary lines between claimed and disclaimed portions of the design.
